UNITED STATES PATENT OFFICE.

ERNEST C. EVERETT, OF NEW YORK, N. Y., ASSIGNOR TO R. E. DIETZ COMPANY, OF NEW YORK, N. Y.

TUBE FOR TUBULAR LANTERNS.

1,202,688.

Specification of Letters Patent. Patented Oct. 24, 1916.

Application filed August 12, 1915. Serial No. 45,155.

To all whom it may concern:

Be it known that I, ERNEST C. EVERETT, a citizen of the United States, residing at New York, in the county of New York and State of New York, have invented a new and useful Improvement in Tubes for Tubular Lanterns, of which the following is a specification.

This invention relates to the construction of frame tubes for tubular lanterns and particularly to that class of lantern frame tubes which have bent ends for connection with the upper and lower portions of the lantern frame and are composed of two stamped half tubes or sections, each of which is of half round cross-section, and which are secured together by interlocking flanges or seams extending along the meeting edges of the half tubes. Unless provision is made for preventing the tube-halves from shifting lengthwise one on the other the tubes will not be rigid but can be easily twisted so that the bent ends will not lie in the same plane, and heretofore in the manufacture of tubular lantern frames considerable difficulty has been experienced in keeping the bent ends of the tubes parallel. If the tubes are twisted ever so slightly the ends thereof will be thrown out of the intended position and the lantern frame when assembled will be faulty in construction, whereas the twisting can be prevented and tubes made strong and rigid by securing the tube halves in such a way as to prevent such relative shifting.

The present invention has for its object to provide an inexpensive and effective construction of the tubes by means of which the twisting thereof is entirely prevented and the tubes are made strong and rigid, and no soldering or tacking of the tube seams is necessary.

In the accompanying drawings: Figure 1 is a fragmentary front elevation of a tubular lantern frame, the side tube of which embodies the invention. Fig. 2 is a side elevation of the lantern tube on an enlarged scale. Fig. 3 is a cross section of the lantern tube taken on line 3—3, Fig. 2.

1 represents one of the air tubes of a tubular lantern of ordinary construction having air tubes at opposite sides thereof connect-

ing the air chamber 2 on the oil pot with the air chamber 3 or chimney at the top of the lantern. Each air tube consists, as usual, of two sections or half-tubes of half round cross-section connected by seams 4 and 5 extending along the meeting edges of the sections at the inner and outer sides of the tube and formed by edge flanges on one tube section folded over edge flanges on the other tube section. These seams securely unite the two tube sections but do not positively prevent one section from shifting lengthwise relative to the other sufficiently to permit the twisting of the tube. In order to prevent such shifting of the tube sections each of the seams 4 and 5 is indented, bent or kinked transversely in one or more places, indicated at 6, so as to form interlocking projections and indentations in the flanges that form the seam. These indentations or bends serve to hold the tube sections rigidly against relative longitudinal movement and positively prevent the tube from twisting, making the tube very strong and rigid. The indentations or bends are exaggerated in the drawings. In practice they are very small and hardly noticeable and do not detract from the appearance of the tube. They can be formed by suitable means in such manner that they do not appreciably add to the expense of manufacture of the tubes and therefore constitute a thoroughly practical and inexpensive means for the intended purpose.

I claim as my invention:

1. A tube for tubular lanterns composed of two tube sections joined by interlocked seam flanges extending along their meeting edges at opposite sides of the tube, said seam flanges being provided at intervals with interlocking bends which prevent relative longitudinal shifting of said sections.

2. A tube for tubular lanterns having two bent ends and composed of tube sections joined by interlocked seam flanges extending lengthwise at the inner and outer sides of the tube, the seam flanges of one tube section being provided with projections which fit in depressions in the seam flanges of the other tube section and prevent the tube from twisting.

3. A tube for tubular lanterns composed of tube sections joined by interlocked seam flanges extending along their meeting edges, said seam flanges being bent at intervals laterally between their ends to form interlocking portions which prevent relative longitudinal shifting of said sections.

Copies of this patent may be obtained for five cents each, by addressing the "Commissioner of Patents, Washington, D. C."

Witness my hand, this 9th day of August, 1915.

ERNEST C. EVERETT.
